UNITED STATES PATENT OFFICE

158,364

LAWN FENCE OR SIMILAR ARTICLE

Samuel W. Ellis, Charlotte, N. C.

Application March 13, 1948, Serial No. 145,080

Term of patent 3½ years

(Cl. D28—1)

To all whom it may concern:

Be it known that I, Samuel W. Ellis, a citizen of the United States, residing at Charlotte, in the county of Mecklenburg and State of North Carolina, have invented a new, original, and ornamental Design for a Lawn Fence or similar article, of which the following is a specification, reference being had to the accompanying drawings, forming a part thereof.

I claim:

The ornamental design for a lawn fence or similar article, substantially as shown.

SAMUEL W. ELLIS.
